UNITED STATES PATENT OFFICE

CHARLES F. MILLER AND SETH W. BRUNDAGE, OF MIAMI, FLORIDA

COMBINED AWNING AND SHUTTER

Application filed March 1, 1929. Serial No. 343,628.

Our invention relates to a protective device for window openings and the like and has for its object the provision of means adapted to serve either as a shutter or a closure for 5 the opening or as an awning therefor.

A principal feature of our invention consists in providing an opening such as a window opening with a plurality of movable sections adapted to be disposed in substantial 10 vertical alinement to close the opening or in overlapping relation to serve as an awning therefor, means being pivotally connected to each of said sections to maintain them in substantially parallel planes in all positions 15 of adjustment they may assume.

Another feature of the invention resides in movably associating a plurality of sections with a window opening which are connected by a plurality of links spaced one above the 20 other, said sections being adapted to be moved into substantial vertical alinement to serve as a closure for the opening or into overlapping relation to serve as an awning therefor.

A further feature of the invention consists 25 in providing a window opening with a plurality of movable sections pivotally connected by a plurality of parallel pairs of links spaced one above the other whereby said sections may move into vertical alinement or into overlapping relation to respectively serve as a 30 closure or as an awning for the opening.

Other and more specific features of the invention residing in advantageous forms and 35 combinations of parts will hereinafter appear and be pointed out in the claims.

In the drawings illustrating a preferred embodiment of the invention:

Figure 1 is a perspective view of the device 40 when serving as a closure for a window opening.

Figure 2 is a similar view of the device in an intermediate position of adjustment.

Figure 3 is a sectional view longitudinally 45 of the window opening, the device being in elevation and in closed position.

Figure 4 is a view similar to Figure 3 showing the device in awning position.

Figure 5 is a fragmentary side elevational 50 view of the device in an intermediate position, the arrows indicating the direction of

movement of the various parts, as the device is being moved from closed to awning position.

Figure 6 is a rear elevational view of the device in closed position. 55

Figure 7 is a sectional view of the lower section of the device.

Figure 8 is an enlarged detailed fragmentary view of the latching mechanism employed for locking the device in closed position. 60

Figure 9 is a sectional view taken on line 9—9, Figure 8.

Figure 10 is an enlarged elevational view showing the connection between the operating cord and operating arm. 65

Referring more particularly to the drawings 1 indicates the wall of a building having an opening 2 within which is mounted a window frame 3 provided with a sash 4 of any desired construction. 70

The protective device for the opening generally consists of two relatively movable upper and lower sections 5 and 6, respectively, which are associated with the window opening and adapted to be moved into either substantial vertical alinement, as clearly shown in Figure 3, to act as a closure for the opening or into overlapping relation, as shown in Figure 4, to serve as an awning for the opening. 75 While it is preferred that these sections be constructed of wood it will be appreciated that any rigid material may be used. When made of wood each of the sections may be advantageously reinforced by a plurality of transversely extending wooden straps or bars 7.

To enhance the appearance of the device the outer faces of the upper section may be covered with any desirable waterproof fabric and the bottoms and sides thereof may be provided with valances as is clearly shown in our co-pending application, Serial No. 339,446. One of the side valances is clearly illustrated at 8 in Figure 4. 80

Disposed above the window opening is an angle iron having flanges 9 and 10, respectively, the former being secured to the outer face of the building by any suitable attaching means 11 and the latter projecting outwardly 85

therefrom substantially normal thereto. The upper section 5 is hingedly connected to the projecting flange 10 by brackets 12, the hinge connection being arranged so that the top edge of the section will lie entirely under the horizontal flange to prevent water and the like from entering between the sections of the window opening.

The lower section 6 is movably associated with the window opening by a plurality of 10 arms 13 respectively pivotally connected by brackets 14 to opposite side edges of the section intermediate its top and bottom edges and by brackets 15 to opposite side edges of 15 the window frame intermediate the top and bottom thereof.

Interposed between the upper and lower sections 5 and 6 for pivotally connecting them are a plurality of pairs of links 16 and 17, 20 respectively. The upper links 16 are secured by brackets 18 to the upper section 5 intermediate the top and bottom edges thereof and they are secured to the lower section by brackets 19 adjacent the upper edge of the latter. The bracket 19 is preferably in the form of a strap of metal which may advantageously extend continuously from the top edge of the lower section to the lower edge thereof. The lower links 17 are secured to 25 the upper section adjacent its lower edge and to the lower section intermediate its top and bottom edges. Brackets 20 may be employed for connecting the links 17 to the upper section. The opposite ends of these links are received within a recess 21 in the member 22 which is interposed between the bracket 19 and the main body portion of the lower section 6. If desired the ends of the upper links 16 which are secured to the lower section 6 and the ends of the links 17 secured 30 to the upper section 5 may be rigidly connected by horizontal portions 23. Since the links are of equal length and as they are spaced apart equal distances on the upper and lower sections it will be perceived that not only are they maintained in parallel planes but that they maintain the sections in parallel planes in all positions of adjustment assumed by the latter.

50 One of the lower links 17 is rigidly fashioned with an extension 24 to which an operating cord 25 or the like may be attached. The window frame 3 is provided adjacent the top and bottom thereof with pulleys 26 for 55 cooperating with the cord 25 so that the device may be conveniently operated from within the building. The opposite ends of the operating cord may advantageously be fashioned with any suitable means 27 for connecting them to the apertured end 28 of the arm 24.

When it is desired to move the sections from the closed position illustrated in Figure 3 to the awning position shown in Figure 4 that portion of the operating cord 25

within the building is pulled downwardly thereby causing rotation of the lower connecting links 17 in a clockwise direction as viewed in Figure 3. Since the ends of the links 17 cannot move downwardly due to 70 their connection with the upper section this rotation of the links will tend to cause an upward movement of the lower section 6. This latter movement of the lower section, however, is resisted by the arms 13 and the 75 result will be that the upper section will rotate in a counter-clockwise direction about its hinge axis causing the parts to assume the position indicated in Figure 5. As the sections continue to move to awning position 80 it will be perceived that the horizontal distances between the opposite ends of the connecting links 16 and 17 continue to increase until the links assume a horizontal position 85 as substantially shown in dotted lines in Figure 4. After they pass through a horizontal position the horizontal distance between their opposite ends starts to decrease and the upper section which has heretofore been rotating in a counter-clockwise direction starts 90 to rotate in the opposite direction. This movement continues until the sections are brought into overlapping engagement and the arms 13 are so proportioned and disposed that when the sections are in this position 95 they are above the horizontal. When the parts assume these positions it will be seen that they have become automatically locked. When it is desired to move the sections from awning to closed position it is only necessary 100 to induce a counter-clockwise rotation of the arm 24 causing the section 5 to rotate upwardly into the dotted line position indicated in Figure 4. After it has assumed this position both sections will move to closed 105 position under the influence of gravity.

110 Latching means is preferably employed for maintaining the sections in closed position. In the present embodiment of the invention this means comprises hooks 29 pivotally associated with opposite sides of the window frame by brackets 30. The outer ends of the hooks are each fashioned with a ledge adapted to engage behind a plate member 31 rigidly secured to the lower reinforcing strip 7 of the upper section 5, the strip being suitably recessed as at 32 behind the plate to receive a portion of the hook.

115 From the foregoing it will be perceived that we have produced a strong and rigid device capable of serving either as a closure or as an awning for window openings and the like.

120 We claim:

125 1. A protective device for a window opening, involving upper and lower sections movable into substantial vertical alinement or into contiguous overlapping relation for respectively serving as a closure or an awning for the opening, said upper section being 130

hingedly mounted adjacent the upper edge of said opening, and means connecting the sections involving a plurality of pivotally mounted rigid members, said members serving to maintain these sections in substantially parallel planes in all positions of adjustment they may assume.

2. A protective device for a window opening, involving upper and lower sections movable into substantial vertical alinement or into contiguous overlapping relation for respectively serving as a closure or an awning for the opening, said upper section being hingedly mounted adjacent the upper edge of said opening, and means connecting said sections involving a plurality of pairs of links pivotally mounted thereon, the pivotal axes of the links on each section being respectively spaced one above the other.

20 3. A protective device for a window opening, involving upper and lower sections movable into substantial vertical alinement or into overlapping relation for respectively serving as a closure or an awning for the opening, said upper section being hingedly mounted adjacent the upper edge of said opening, a plurality of links pivotally connecting said sections, said links being connected to each section one above the other, the upper one of said links being secured to the upper section intermediate the top and bottom edges thereof and to the lower section adjacent its upper edge and the lower one of said links being secured to the upper section adjacent its lower edge and to the lower section intermediate the top and bottom edges thereof, said links being arranged to maintain said sections in substantially parallel planes in all positions of adjustment.

40 4. A protective device for a window opening, involving upper and lower sections movable into substantial vertical alinement or into contiguous overlapping relation for respectively serving as a closure or an awning for the opening, said upper section being hingedly mounted adjacent the upper edge of said opening, and means connecting said sections involving two pairs of links respectively pivotally mounted on each section one above the other.

50 5. A protective device for a window opening, involving upper and lower sections movable into substantial vertical alinement or into overlapping relation for respectively serving as a closure or as an awning for the opening, said upper section being hingedly mounted adjacent the upper edge of said opening, and means pivotally connecting said sections involving a plurality of pairs of links respectively connected to each section one above the other, the upper one of said pairs of links being secured to the upper section intermediate the top and bottom edges thereof and to the lower section adjacent its upper edge and the lower one of said pairs of

links being secured to the upper section adjacent its lower edge and to the lower section intermediate the top and bottom edges thereof.

6. A protective device for a window opening, involving upper and lower sections movable into substantial vertical alinement or into contiguous overlapping relation for respectively serving as a closure or an awning for the opening, said upper section being hingedly mounted adjacent the upper edge of said opening, said lower section being movably associated with said opening below the hinge axis of the upper section, and means connecting the sections involving two pairs of pivotally mounted rigid members, said members serving to maintain these sections in substantially parallel planes in all positions of adjustment said sections may assume.

7. A protective device for a window opening, involving upper and lower sections movable into substantial vertical alinement or into overlapping relation for respectively serving as a closure or an awning for the opening, said upper section being hingedly mounted adjacent the upper edge of said opening, and a plurality of links pivotally connecting said sections, the pivotal axes of the links of each section being respectively spaced one above the other, one of said links having a rigid portion adapted to actuate said sections.

8. A protective device for a window opening, involving upper and lower sections movable into substantial vertical alinement or into overlapping relation for respectively serving as a closure or an awning for the opening, said upper section being hingedly mounted adjacent the upper edge of said opening, and means pivotally connecting said sections involving a plurality of parallel links respectively connected to each section one above the other.

9. A protective device for a window opening, involving upper and lower sections movable into substantial vertical alinement or into overlapping relation for respectively serving as a closure or an awning for the opening, said upper section being hingedly mounted adjacent the upper edge of said opening, means pivotally connecting said sections involving a plurality of pairs of links respectively connected to each section one above the other, one of said pairs of links having a rigid extension constituting an arm for operating said sections.

10. A protective device for a window opening, involving upper and lower sections movable into substantial vertical alinement or into overlapping relation for respectively serving as a closure or an awning for the opening, said upper section being hingedly mounted adjacent the upper edge of said opening, means for movably associating said lower section with the opening, said means involv-

ing a plurality of links respectively disposed adjacent opposite side edges of the lower section and pivotally connected to the latter, and a plurality of links for pivotally connecting said sections, the pivotal axes of the links on each section being respectively spaced one above the other, and means operatively associated with one of said links for actuating said sections.

10 In testimony whereof we affix our signatures.

CHARLES F. MILLER.
